Patented Oct. 6, 1914.

UNITED STATES PATENT OFFICE.

JOHN J. WALKOWC, OF DETROIT, MICHIGAN.

FOUNTAIN-PEN POINT.

1,112,870.

Specification of Letters Patent.

Patented Oct. 6, 1914.

Application filed June 5, 1913. Serial No. 771,939.

To all whom it may concern:

Be it known that I, JOHN J. WALKOWC, citizen of the United States, residing at Detroit, in the county of Wayne and State of Michigan, have invented certain new and useful Improvements in Fountain-Pen Points, of which the following is a specification.

This invention relates to improvements in fountain pens, and has for one of its objects to provide a simply constructed attachment which may be applied to a pen point, and whereby a reservoir of ink is furnished and arranged in position to feed automatically 15 to the pen point as fast as required.

Another object of the invention is to provide a simply constructed device whereby the ink is uniformly distributed and guided to the writing end of the pen, and prevented 20 from "flooding" the pen point.

With these and other objects in view the invention consists in certain novel features of construction as hereafter shown and described and then specifically pointed out in 25 the claims.

Figure 1 is a front elevation of a pen point with the improvement applied. Fig. 2 is a side view of the same partly in section. Fig. 3 is a transverse section on the line 3—3 of 30 Fig. 1.

Corresponding and like parts are referred to in the following description and indicated in all the views of the drawings by the same reference characters.

The improved device may be applied to 35 any of the various forms of pen points, but for the purpose of illustration is shown applied to a conventional pen point represented at 10 with the longitudinal split in 40 its nib end as shown at 11 and an aperture at 12 at the inner end of the split.

In the improved pen point a hollow channel is formed at the inner end of the aperture 12 and extending longitudinally of the 45 body of the pen point for a short distance. Attached to the back of the pen point at the upper end of the channel 13 is a small ink receptacle, represented as a whole at 14, and preferably converging at the lower end as 50 represented at 15. At the terminal of the converging portion 15 a relatively small orifice 17 is formed which is located above the

inner end of the channel 13, and thus conveys the ink to the channel and thence through the opening 12 to the under side of 55 the writing end of the pen.

The orifice 17 is just large enough to permit the ink to slowly drip through to the channel 13 and thence through the opening 12 to the pen point, but will not flow faster 60 than required while writing. The channel 13 thus receives the ink and guides it to the aperture and effectually prevents all danger of the flooding of the "point."

The improved device is simple in construction and can be inexpensively applied to 65 various forms of pen points.

Having thus described the invention what is claimed as new is:

1. A split nib pen point including an 70 aperture at the inner end of the split with a longitudinally directed channel communicating with the aperture, and an ink reservoir carried by the pen point and having a discharge orifice communicating with the 75 channel.

2. A split nib pen point including an aperture at the inner end of the split and a longitudinally directed channel communicating with the aperture, and an ink reservoir carried by the pen point and converging at one 80 end and having a discharge orifice at the converging end communicating with the channel.

3. A split nib pen point having a longitudinally directed channel, an ink reservoir carried by the pen point and having a discharge orifice communicating with the channel, and communicating means between the channel of the underface of the pen point. 85

4. The combination with a split nib pen point including an aperture at the upper terminal of the split and with a channel communicating with the upper end of the aperture, of an ink reservoir attached to the 90 pen point and having an ink orifice providing for the discharge from the reservoir into the channel. 95

In testimony whereof I affix my signature in presence of two witnesses.

JOHN J. WALKOWC. [L. S.]

Witnesses:

JOSEPH PIEPER,
BROTHER MACARIUS.
